FORMATION OF ARTIFICIAL MARBLE

Arvid E. Larson, Salt Lake City, Utah

Application February 25, 1933, Serial No. 658,672

2 Claims. (Cl. 41—26)

My invention relates to laying and formation of imitation marble composition flooring and has for its object to provide an artificial marble which in all appearances has all the qualities of 5 marble and is just as decorative as though real marble had been used.

A further object is to provide an imitation marble flooring in which the different colored veins are laid therein and therethrough and which 10 still retains this grained effect throughout the entire thickness of the material so that no amount of wear will change the appearance thereof.

A still further object is to provide a system of 15 making and laying imitation marble, creating marble effect, which does not have an artificial appearance and which may be laid in any desired shape or design.

Figure 1 is a side elevation of the material laminated, one layer upon the other, and all laid 20 upon a cloth base preparatory to rolling the material.

Figure 2 is a side elevation of Figure 1 with the end of the cloth raised and the roll started.

Figure 3 is a view of the roll with dotted lines 25 to indicate the directions of cutting the material to vary the pattern.

Figure 4 is a sectional view of the material in the roll as it would look when the cut had been made along the dotted line 4—4 of Figure 3.

Figure 5 is a sectional view of the material in 30 the roll as it would look when cut along the diagonal dotted line 5—5 of Figure 3.

In the drawing A represents the canvas or cloth on which the layers 1, 2, and 3 of the material are placed. These layers 1, 2, and 3 may be made or mixed of different colored materials as described hereafter, to give the effect of marble, or may have the color dry and dusted on the surface to give such effect.

40 These objects I accomplish with the method and process hereinafter set forth.

Onto a piece of oilcloth or similar material I lay a thickness of any color mixed material which has already been moistened and mixed to the 45 proper constituency. This layer is preferably about one half inch thick. Superimposed onto this layer I then lay other layers of like material either a like color or a different color until the desired number of colors and mixtures of colors 50 has been obtained. This makes a stack of layers of mixed material resting one upon the other.

Each separate color is mixed in a separate container and laid onto the stack of colors as desired, and the thickness of the different colored 55 veins desired is controlled by the thickness of the

layers. If a thin vein is desired I mix half dry color and half dry material and spread out and force into the adjacent layer with a trowel.

When the desired amount of various colors is spread out one on top of the other as before described, I take two adjoining ends or sides of the cloth on which the layers are spread and pull it up over itself toward the center which causes the material to roll into a round roll or loaf with the colors in helical effect therein when looking 60 at one end thereof. I then cut the roll into desired slices, the slices through the roll to depend upon the desired effect wanted in the resulting 65 floor or wall.

If a long veined effect is desired, I cut the roll 70 lengthwise but if a cross grained effect is desired, I cut the roll across at right angles to the longitudinal axis. The roll may be cut through at any angle with each angle making a different effect in the resulting material. These cuts are 75 then laid in places already prepared with thickness strips set in the positions desired. The surface of the material is then spread around with a trowel, and the strips removed, and some of the material from the cut is placed in the opening 80 left by the removal of the strips and the entire surface is then smoothed down by a trowel.

As soon as the material has set sufficiently hard it may either be hand scraped or may be smoothed 85 down by any sanding machine. It is then waxed and polished to the desired finish.

Having thus described my invention I desire to secure by Letters Patent and claim:—

1. A method of forming artificial marble, comprising laying laminated colors of already moistened and mixed material upon a sheet of oilcloth, rolling the laminated colors into a roll by raising two of the corners of the cloth, cutting the roll for the desired effect, laying the cut on the desired surface and smoothing the entire surface 90 by trowel.

2. A method of forming artificial marble, comprising laying layers of various colors upon an oilcloth, rolling the cloth to form a roll of the layers thereon, cutting the roll longitudinally to 100 form long grained effect laying the cuts in any desired surface by smoothing the top surface down with a trowel, and finishing the entire surface by sand papering and scraping to the desired smoothness.

ARVID E. LARSON.
